CHICK TRAINER

Filed Feb. 25, 1930

UNITED STATES PATENT OFFICE

MARTHA KLAUDT, OF DOLTON, SOUTH DAKOTA

CHICK TRAINER

Application filed February 25, 1930. Serial No. 431,163.

This invention relates to chick trainers, and an object of the invention is to provide a hawk simulating body which when operated will instinctively scare chicks to cover when it is the desire of the poultryman to chase them into their coops.

Further objects of the invention are to provide a device of the character referred to that is strong, compact and durable, thoroughly reliable for its intended purpose, very simple in its method of assembly, and comparatively inexpensive to manufacture and operate.

With the foregoing and other objects in view, the invention consists of a novel construction, combination and arrangement of parts, as will be hereinafter more specifically described and illustrated in the accompanying drawings, wherein is disclosed an embodiment of the invention, but it is to be understood that changes, variations and modifications, may be resorted to without departing from the spirit of the claims hereto appended.

In the drawings wherein like numerals of reference denote corresponding parts throughout the several views:—

Figure 1 is a vertical sectional view thru the handle showing in, inner side elevation, one of the sections of the body coupled therewith,

Fig. 2 is a side elevation thereof,

Fig. 3 is a top plan view partly broken away and showing the body thereof, and

Figure 4 is a fragmentary plan view of the operating cable and the branches leading therefrom.

Referring to the drawings in detail, 4 indicates generally a hawk simulating body preferably formed of tin. The body is made with a head 5 on its forward end and a tail 6 on its rear end. The body is formed in two sections 7, 8 secured together by bolts 9, 10 that extend through the sections of the body and secure them together.

The interior of the body 4 is formed with a vertical pocket 11 that opens out through the bottom of the body. Extending from each side of the body into the pocket are a pair of horizontal slots 12. A pair of laterally extending wings 13, 14 project laterally from the body and on their inner edges are

formed with a pair of tongue extensions 15, 16 that extend through the slots 12 into the pocket.

Each of the wings 13, 14 are hinged to the side of the body as at 17. Another pocket 18 is formed in the body forwardly of pocket 11 and mounted in this pocket is a bellows 19. Extending from the pocket 18 forwardly, is a passage in which is seated a tube 20 that is connected at one end with the bellows, and at its outer end to a whistle 21 seated in a pocket in the head.

Leading from the rear end of the pocket 18 is a passage 22 that communicates with a lower portion of pocket 11. The body 4 is supported on the upper end of a handle 23 which is secured within the lower portion of pocket 11. The handle 23 is provided with an axial bore 24 that extends entirely through the handle. The lower end of bore 24 is enlarged as at 25 to receive a coil spring 26, the lower end of which is anchored as at 27 to one wall of the enlarged portion 25.

The upper end of the coil spring 26 is secured to the lower end of a cable 28 that extends through the bore 24. A slot 29 is formed in the side wall of the handle 23 and communicates with the bore 24. Secured to the cable 28 and projecting through the slot 29 is an operating trigger 30 by which the cable is moved up and down.

At the extreme upper end, the cable is formed with two branches 31, 32 that are secured to the inner ends of the tongues 15, 16 on the wings by means of staples 33. One end of a coil spring 34 is connected to the crotch of the branches as at 35, while the other end is secured to a staple 36 anchored in the side wall of pocket 11. A branch 37 leads from the cable 28, through the passage 22, and is secured to the inner end bellows 19. The extension or branches 31, 32 and 37 are rigid, while the cable 28 is flexible.

To make the hawk simulating body more artistic, the body and tail is painted in silver, edged in black, while the beak is painted yellow, the eyes brown, and a black rim around the eyes. Young chickens instinctively are afraid of hawks. It is one of the difficulties

of the poultryman to teach a young chicken to come to cover at a signal.

Now in using the hawk simulating body with the whistle and flapping of the wings, the young chickens are at first scared to cover. After repeated use of the chicken trainer upon seeing the device in the poultryman's hands will know that it is his desire to have them come to cover. In this way, the young chickens are broken or trained to come to cover whenever the device is in the hands of the poultryman.

In the operation of the invention, the poultryman moves the trigger 30 up and down, which movement causes the wings to flap up and down and the bellows to force air into the whistle 21 and make an audible sound.

The present embodiment of the invention has been disclosed in considerable detail merely for the purpose of exemplification, since in actual practice it attains the features of advantage enumerated as desirable in the statement of the invention and the above description.

It is to be understood that by describing in detail herein any particular form, structure, or arrangement, it is not intended to limit the invention beyond the terms of the several claims, or the requirements of the prior art.

Having thus described my invention, what I claim as new is:—

1. A chick trainer comprising a hawk simulating body, a handle secured to the body having an axial bore, said body having spaced pockets that communicate with said bore, slots on the opposite sides of the body extending into one pocket, a pair of wings hingedly connected to the body and having tongue extensions on their confronting ends projecting through said slots into said one pocket, a whistle seated in the forward portion of said body, said body having a passage leading from the whistle to the other pocket, bellows movable in said other pocket, a cable resiliently connected at its lower end to the outer end of the handle, and extending through said bore, branch extensions on the upper end of the cable connected to the bellows and the tongues of each wing, a spring connected to the upper end of the cable and to a wall of the said one pocket, and means for moving the cable.

2. A chick trainer comprising a hawk simulating body, a handle secured to the body having an axial bore, said body having spaced pockets that communicate with said bore, slots on the opposite sides of the body extending into one pocket, a pair of wings hingedly connected to the body and having tongue extensions on their confronting ends projecting through said slots into said one pocket, a whistle seated in the forward portion of said body, said body having a passage leading from the whistle to the other pocket,

bellows movable in said other pocket, a cable resiliently connected at its lower end to the outer end of the handle, and extending through said bore, branch extensions on the upper end of the cable connected to the bellows and the tongues of each wing, a spring connected to the upper end of the cable and to a wall of the said one pocket, means for moving the cable, and said means including a trigger on the cable, and said handle formed with a slot that communicates with the bore in which the trigger is slidable.

3. A chick trainer comprising a hawk simulating body, a handle secured to the body having an axial bore, said body having spaced pockets that communicate with said bore, slots on the opposite sides of the body extending into one pocket, a pair of wings hingedly connected to the body and having tongue extensions on their confronting ends projecting through said slots into said one pocket, a whistle seated in the forward portion of said body, said body having a passage leading from the whistle to the other pocket, bellows movable in said other pocket, a cable resiliently connected at its lower end to the outer end of the handle, and extending through said bore, branch extensions on the upper end of the cable connected to the bellows and the tongues of each wing, a spring connected to the upper end of the cable and to a wall of the said one pocket, means for moving the cable, said means including a trigger on the cable, said handle formed with a slot that communicates with the bore in which the trigger is slidable, and said branches being rigid.

4. A chick trainer comprising a hawk simulating body, an audible signal in the body, a bellows supported in the body and operatively connected to the audible signal, wings rockably connected to the body and having their confronting ends extending into the body, a handle connected to the body having a bore therein communicating with the interior of the body, a cable extending through the bore having branches on one end connected to the bellows and wings, and means connected to the cable extending exteriorly of the handle for moving the cables to operate the wings and audible signal.

In testimony whereof I affix my signature.
MARTHA KLAUDT.
